COMBINED TYPEWRITING AND COMPUTING MACHINE

Walter T. Sagner, West Hartford, Conn., assignor to Underwood Elliott Fisher Company, New York, N. Y., a corporation of Delaware

Application January 28, 1933, Serial No. 653,960

6 Claims. (Cl. 235—60)

This invention is an improvement on that covered by U. S. patent to Hart No. 1,238,908, issued Sept. 4, 1917 and relates to a combined typewriting and bookkeeping machine, and more particularly to the automatic motor-trip device for causing the machine to cycle and run a key-set amount into the register.

In the Underwood bookkeeping machine, the typing of an amount in a computing column causes the amount to be set up or indexed, preparatory to accumulating the amount in a register. Upon the typing of the last of the digits, the typewriter-carriage will escape when the type-bar recoils from the platen. A tappet that is mounted on the moving carriage will, as the carriage escapes, at once rock a motor-tripping lever, to cycle the mechanism that runs the indexed amount into the register. This incidentally clears the indexing mechanism.

20 The operator may now operate a carriage-return key, to return the carriage preparatory to writing the next item on the sheet.

It has been found that an operator is apt at times to operate the carriage-return key prematurely. When this is done, it results that the carriage starts to return before the last operated type-bar has recoiled from the platen and released the escapement. In consequence, the carriage will fail to feed. Hence the tappet on the carriage will fail to operate the trip-lever, and therefore the carriage returns without the adding mechanism being cycled. In other words, the indexing mechanism will remain all set, but no amount has been run into the register.

25 The operator has no way of knowing that the machine has failed to cycle, and is apt to continue his work, typing the next number on the work-sheet. This new typing, however, will operate the pin-indexing mechanism and thereby change the previously indexed but uncycled amount. When the machine comes to cycle, there is no way of telling what amount is run into the register. It is evident that the indexing of two separate numbers would cause more than one pin to be set upon each of one or more pin-bars.

30 The present invention eliminates the trouble referred to. A two-part tripping means is provided and is preferably in the form of a two-part dog-device placed upon the tripping lever, so that (even if the carriage is returned prematurely, or without the cycling mechanism being tripped) a second part of the novel two-part dog-device will be engaged by the tappet on the returning carriage, and cause the machine to cycle, thereby making sure that the machine cycles and

the amount is run into the register even if the carriage is returned too soon.

In the Underwood bookkeeping machine Patent No. 1,280,065 to Minton, the tappet on the carriage is shown tripping a dog to initiate the cycling.

The invention may be practised by providing in conjunction with said dog, a separate cycling dog to form with the first dog the two-part dog-device, arranged with respect to the zone-tappet so that the latter idly passes the separate dog in the forward-carriage movement but becomes effective to trip the separate dog for a machine cycle at the start of the carriage-return movement which follows the typing of the last figure in any zone.

The first cycling dog may be a cam-nose presented in the path of the carriage-tappets by the movable cycling member or tripping lever which is thus operative to cycle the machine, the cam-nose and tappets being arranged so that said member may be operated in one step of the carriage advance movement in order to provide for cross-computing.

The separate cycling dog may be an extra cam-piece carried by said member, said extra cam-piece being arranged and spaced from the first cam-nose, so that, in any zone, it is idly bypassed by the zone-tappet before the latter in the forward carriage movement reaches the regular cam-nose position. In the return carriage movement, said extra cam-piece, however, when overridden by the zone-tappet, becomes effective, in lieu of the first dog, to cycle the machine, should the carriage be returned prematurely in such wise as to prevent the carriage from taking the final letter-feeding step on which the first dog depended to come into play.

The invention thus provides for successive zone-cycling during the advance of the carriage for cross-computing and also prevents the aforesaid omission of a machine cycle in fast operation of the machine.

Other features and advantages will hereinafter appear.

In the accompanying drawing,

Figure 1 is a front elevation showing the novel cycling dog arrangement on the cycling member.

Figure 2 is a cross-section view of the Underwood bookkeeping machine in which the invention is illustratively embodied.

Figure 3 is a perspective view of part of the typewriter-carriage, escapement-devices, and

carriage-return mechanism, illustrating the operation of the novel cycling dogs.

Figure 4 is a front elevation of the cycling lever, showing how the same may be operated in the carriage-return movement by means of the novel cycling dog arrangement.

Figure 5 is a top-plan view of the cycling member, showing details of construction.

Depression of any numeral-key 10, Figure 2, 10 on key-lever 11, fulcrumed at 12, swings the usual bell-crank 13 to swing type-bar 14 toward platen 15. When the type-bar 14 is about to print the usual heel 16 thereof moves a universal bar 17 rearwardly to swing the usual dog-rocker 18 and interpose a fixed dog 19 thereon into the plane of an escapement-wheel 20 as seen in Figure 3. A stepping dog 21 seen in Figure 2 on the dog-rocker thereupon escapes. The escapement-wheel 20 and co-operating dogs 19 and 21 control the letter-feed movements of a carriage 23 in which the platen 15 is journaled, the carriage being urged in letter-feeding direction by spring-motor 24, having the usual draw-band connected to the carriage at 25. The carriage has the usual letter-feed rack 26 which meshes with a pinion 27 connected to the escapement-wheel 20.

The numeral-type keys 10 are operated to print upon a work-sheet 30, on which several computing zones 31, Figure 3, may be arranged. 30 At each zone the amount is indexed in a computing base 32, having totalizing wheels 33 rotatable by denominational rack-bars 34 and carrying devices (not shown), each bar carrying a row of depressible digit-pins 35. By means of a pendent link 36, each numeral-key lever 11, when operated, actuates a corresponding one of the usual group of pin-setting linkages 37 to set a corresponding digit-pin 35. The rack-bars 34 are normally in such position that the pins 35 therein are offset rearwardly from pin-setting bars 38 of said pin-setting linkages 37, and are advanced seriatim to bring their pins under said bars 38 as the carriage 23 travels through a computing zone. For each zone, the carriage 23 carries a denomination-determining tappet 40 to operate a series of pivoted jacks 41 corresponding to the several rack-bars 34. Each jack 41 is part of a denomination-selecting train which includes a push-rod 42 through which the jack 41 operates the usual transposing linkage 43 to advance the rack-bar 34 sufficiently against the force of its retracting spring 44 to bring the pins 35 under the pin-setting bars 38.

The setting of the pins 35 projects their lower ends into the path of the usual reciprocatory cross-bar 46, normally in the position seen in Figure 2, and which is given a forward and return movement for cycling of the machine during which said bar advances the several rack-bars 34 to extents corresponding to the value of set pins 35. Said cross-bar 46 is part of a general operator 47 driven by a reciprocatory arm 48 connected by means of a clutch within a casing 49 to a driving motor 50, the clutch operating to so connect said arm 48 by upward retraction of a clutch-pin 51 at the top of the casing.

The typewriter-carriage 23 is tabulated to a computing zone by means of the usual denominational tabulating mechanism which includes a series of denominational stops 52, Figure 2, which are individually projectable by tabulating keys, not shown, into the path of zone-stops 53 settable along the usual notched bar 54 carried by 75 the typewriter-carriage.

Each zone-stop 53 is also used as a zone-tappet for tripping a cycling member from which extends a train of mechanism for retracting the clutch-pin 51 to initiate a machine cycle. Said cycling member is a lever 55 pivoted as seen in Figure 2 to a column 56 in which the denominational stops 52 are retained. The lever 55 is pivoted on a stud 57 projecting from said column and is built up of parallel plates 59 and 60, Figure 5, spaced apart by a double shouldered collar 61, Figure 5, which forms the lever-hub. The plate 60 includes a lever-arm 62 extending to the right of the pivot 57, as seen in Figure 3. Both plates 59 and 60 form an arm 63, Figure 1, extending to the left side of the pivot 57, the plates being spaced apart at the end of said arm 63 by a double shouldered spacer 64.

For operation of the lever 55 by any one of the zone-tappets 53 in the forward movement of the carriage, the lever-arm 63, Figure 1, presents in the path of said tappets a cam-nose 66 projecting from between the plates 59 and 60 and pivoted upon a stud 67 extending through said plates. The piece forming the cam-nose 66 normally abuts the end of a screw 69 threaded into the spacer 64. By means of the screw 69 the cam-nose 66 may be adjusted so that the zone-tappet co-operates therewith to swing the lever 55 in one letter-feeding step of the carriage. The lever 55 is so operated by the tappet 53 for initiating a machine cycle as the carriage takes the letter-feeding step which ensues upon the typing of the last figure of the amount in the computing zone.

The train of connections between the cycling lever 55 and the retractile clutch-pin 51 includes a link 71 extending downwardly from the lever-arm 62 to the usual lever 73 which has offset arms, as seen in Figure 2, and which is pivoted upon a rod 74 in the computing base 32. 40 The inner arm of the lever 73 is connected to one end of the usual retractile latch-bar 75, the other end of which is supported to normally overlie an arm 76 of a lever 78, seen in Figure 2, and pivoted to the machine-frame at 77. The lever-arm 76 is urged upwardly by a spring 79 which, when the latch-bar 75 is retracted, causes the lever 78 to be rocked so that an opposite arm 80 thereof, which overlies a projection 81 extending from a slide 82, may depress said slide 50 and rock the usual lever 83 whereby the clutch-pin 51 is retracted.

By the described train of connections, the machine is caused to be cycled as the last figure of a zone-amount is typed, the cycling operation 55 causing the amount to be accumulated in the dials 33, and also causing by the usual means restoration of the pins 35 so that the indexing mechanism will be cleared for indexing a following item, said following item being set up in 60 the same set of rack-bars 34 as was the preceding item. There is a zone-tappet 53 for every column or zone 31 on the work-sheet 30, the machine being cycled for every amount printed on said sheet. The pin-restoring means are diagrammatically indicated in Figure 2 and are of the kind fully described in Hanson Patent 1,279,-863, dated September 24, 1918. Said pin-restoring means include a plate 28 coextensive with the configuration of pins 35 presented by all the 70 drive-racks 34. The general operator 47 carries a pawl 39, which, through the medium of a shaft 29, momentarily raises the plate 28 to restore any set pins 35 just before the general operator 47 completes its return stroke.

The work-sheet 30, Figure 3, exemplifies a simple account in which cross-computing is done. At the first line, the amount 21.50 is typed in the last column to represent the initial balance, and 5 is at the same time, as soon as the last digit is printed, caused to be accumulated in the wheels 33 by cycling the machine. The first item is the debit-item 7.20 which is typed, after a line-spacing and carriage-return operation, in the 10 second line, first column, pursuant to which the machine is automatically cycled by means of the forwardly-acting dog 66 to cause said debit-amount to be subtractively entered into the register-wheels 33 which then show a balance of 15 28.70. The carriage now is advanced to bring the third or balance column into use to copy said balance and to incidentally set it up subtractively in the register-bars 34. Upon typing of the last figure of the balance 28.70 in said third 20 column, the machine is again cycled, causing the register-wheels to be cleared. Entry on said work-sheet of the next item at a future date is accompanied by copying, in the same line as the previous item, the balance of 28.70 in the fourth 25 or last column, in order that said balance may be set up in the register-wheels preparatory to entering said next item on the next line and computing a new balance. It will be seen that the aforesaid sheet 30 represents one of the simplest 30 forms of cross-computing, to illustrate one purpose of the invention, namely, that the machine shall be capable of cycling repeatedly during the forward movement of the carriage, and that a cycle shall be initiated automatically as the 35 carriage takes the usual letter-feeding step following the typing of the last figure of an amount. This cycling of the machine in immediate sequence to the typing of the last figure is desirable in order that the carriage need not take any 40 further advance step preparatory to returning the carriage from any zone. Usually, in the above-described example, the carriage is returned after printing the balance in the third column and initiating a cycle for clearing the register- 45 wheels.

At the end of the typing in any line on the work-sheet 30, a power-driven carriage-return mechanism which may be similar to the one shown in Patent No. 1,580,326, to H. L. Pitman, 50 is brought into use. Said carriage-return mechanism includes a manually-operable lever 86, pivoted at 87, and having a key 88 adjacent the typewriter-keyboard, as seen in Figure 2. Said lever 86 is operative to raise the forward end of a link 85 and thereby release the latter which is normally caught over a holding plate 89.

The released link 85 is pulled rearwardly by a spring 90 to rock a shaft 91, to which is fastened a downwardly-extending arm 92, to which the 60 rear end of the link is pivoted. Another arm 93 fastened to the rock-shaft 91 is connected by a link 94 to an arm 95 of rock-shaft 96 which has an arm 97 articulated, as seen in Figure 2, to a carriage-return pinion 98 which meshes with 65 a rack 99 upon the typewriter-carriage 23, the pinion 98 being slidable in axial direction upon shaft 100 and having clutch-teeth 101 which may engage a clutch 102 fastened to said shaft 100 which is journaled in a bracket 103 of the machine-frame. The shaft 100 carries a pulley 104 connected by a belt 105 to the electric motor 50 (see Patent No. 1,238,908 to F. A. Hart). The motor is normally silent and is only energized when the machine has to be cycled or the carriage 70 75 23 is to be returned. A switch within cas-

ing 106 is closed by means of a link 108 extended from the described carriage-return-initiating train.

In fast operation of the machine, the operator may press the carriage-return key 88 in such 5 rapid sequence to release of the numeral-key 10, operated for typing the last figure of an amount, that the carriage-return movement is caused to start before the carriage has had time to take the letter-feed step on which initiation of 10 the required machine cycle depends. Figure 3 illustrates this condition by showing engagement of the carriage-return pinion 98 with the clutch-member 102, both being under rotation on account of pressing the carriage-return key before 15 rebound of the type-bar 14 and consequently before the carriage has had time to escape for actuation of the regular cycling dog 66 by the zone-tappet 53 following such rebound. This condition arises, as shown, for example, in Figure 20 3, when the carriage is to be returned after the typing of only a single amount in a line, as when several items are entered on successive lines before clearing the register-wheels, and it may result that the required machine cycle is omitted. Such omission not being readily noticeable, an error in computation may result.

For preventing such omission of the machine cycle, there is provided upon the cycling lever 55 a separate cycling dog which may be an extra 30 cam-piece 107 projecting from between the lever-plates 59 and 60 and pivoted upon a stud 109 extending crosswise of said plates. The cam-piece 107, in its normal position, abuts the side of the collar 61, as seen in Figure 1, and is yieldably held against said collar 61 so that it may be by-passed by any one of the zone-tappets 53 in the forward movement of the carriage, the cam-piece 107 being thus inoperative for tripping the cycling lever 55 during such forward 40 movement. The cam-piece 107 has an arm 110 to which is applied a spring 111 anchored to the lever 55 at 112 for yieldably holding the cam-piece against said collar 61.

The extra cam-piece may be so spaced from 45 the regular dog or cam-nose 66 that, as seen in Figure 3, it becomes operative to actuate the cycling lever 55 for initiating a machine cycle at the start of the carriage-return movement. Thus the machine will be properly cycled even though 50 the zone-tappet 53 does not reach the regular cycling dog or cam-nose 66 on account of premature operation of the carriage-return key. But when the carriage-return key is properly operated so that the regular cycling dog 66 takes effect the reversely-acting dog 107 is idle in that 55 it does not initiate a cycle.

Figure 4 illustrates the zone-tappet 53 overriding the extra cam-piece 107 and causing the cycling lever 55 to be operated for initiating 60 a cycle by the return movement of the carriage. Figure 1 illustrates by dot-and-dash outline 107^a how the extra cam-piece 107 may be idly bypassed by the zone-tappet 53 in the forward movement of the carriage. Where a tappet 53 65 has passed the cam-nose 66, the latter, on account of its free pivoting, may in the return movement of the carriage assume the dot-and-dash position 66^a, Figure 4, against the cam-piece 107. This is no moment, however, since the 70 stud 67 is so disposed relatively to the tip of the cam-nose 66 that with the cycling lever in normal position, said tip is still in the path of the zone-stops in the position 66^a, and that consequently the cam-nose 66, freely pivoted, is caused to be 75

restored to its normal position against the adjusting screw 69 by forward movement of the carriage.

It will be understood that in the forward carriage-movement a tappet 53 passes the cam-nose 66 either when there are used several of said tappets or, if only one tappet is used, when the carriage has normally escaped at the writing of the last figure of an amount.

10 It will be understood that the invention is not limited to use in conjunction with a cam-nose 66 mounted as thus described so long as said regular cam-nose is operative or the machine is otherwise cycled in the forward carriage-movement:

15 The denomination-selecting tappets 40 are raised to operative position during the travel of the carriage through a computing zone by the usual support 113, Figure 2, said support being withdrawn during a machine cycle. The carriage 20 travels on the usual rails 114 and 115, supported in the typewriter-frame 116.

25 The usual spring 117 co-operates with the usual stopping means to yieldably hold the cycling lever 55 in normal position, wherein the cam-nose 66 and the extra cam-piece 107 are in the path of the zone-tappets 53.

30 Variations may be resorted to within the scope of the invention, and portions of the improvements may be used without others.

Having thus described my invention, I claim:

35 1. In a combined typewriting and computing machine, the combination with numeral-type keys, a co-operative letter-feeding carriage, means in which an amount is set up at any carriage travel computing-zone by said keys and carriage preparatory to a cycling operation at said zone, and key-operated power-driven carriage-return mechanism, of carriage-controlled cycling mechanism including tripping means having a two-part dog-device engageable with tappet-means at each computing-zone, the first part of said two-part dog-device being engaged with the tappet-means as the carriage takes the letter-feeding 40 step following operation of a numeral-key to type and set up the last figure in an amount for said zone, to thereby trip the cycling mechanism for clearing the set-up means preparatory to operation in the next zone, the second part of said 45 two-part dog-device being idly by-passed by said tappet-means before the latter is engaged with the first part of said two-part dog-device, whereby said tappet-means and said second part, in lieu of said first part, of said two-part dog-device become effective to operate said tripping means during a carriage-return movement started by operation of the carriage-return mechanism-key in such rapid sequence to operating 50 the last figure numeral-key that the carriage fails to take the usual letter-feeding step on which depended operation of said tripping means by means of the first part of said two-part dog-device.

55 2. In a combined typewriting and computing machine, the combination with numeral-type keys, a step-by-step feeding carriage, power-driven mechanism for returning said carriage, a starting key for said returning mechanism, and set-up means in which an amount is set up under the control of said keys and carriage preparatory to a cycling operation, of cycling mechanism automatically operated by said carriage at each of successive zones of the carriage travel to accumulate the amount for said zone in a set of 60 register-wheels and clear said set-up means pre-

paratory to setting up an amount for the next zone, said cycling mechanism including a plurality of carriage-tappets, one for each zone and adjustable therefor on the carriage, and a member presenting a two-part dog-device, said member operable by any tappet and connected to trip said cycling mechanism, the first part of said two-part dog-device presented by said member being engaged by said tappet to trip the cycling mechanism as the carriage advances after the setting up of the last figure of an amount in a zone corresponding to said tappet, the second part of said two-part dog-device presented by said member being idly by-passed by said tappet before the latter engages the first part of 10 said two-part dog-device, whereby said tappet and said second part, in lieu of said first part, of said two-part dog-device become effective to actuate said member and trip said cycling mechanism during a return movement of the carriage 20 from the zone should said return movement be started prematurely in such wise as to prevent the carriage from taking said step upon which the first part of said two-part dog-device depended to come into play.

25 3. In a combined typewriting and computing machine, the combination with numeral-keys, a co-operative step-by-step feeding carriage, power-drive mechanism for returning said carriage, a starting key for said returning mechanism, 30 a totalizer, indexing means whereby an amount is set up by means of said keys and carriage at different computing zones of the latter, and cycling mechanism operable to accumulate the indexed amount in said totalizer and clear the 35 indexing mechanism, of carriage-controlled means for automatically tripping the cycling mechanism, said carriage-controlled means including a two-part dog-device and complementary means, said two-part dog-device and complementary means coacting by means of the carriage movement to trip the cycling mechanism, the first part of said two-part dog-device coacting with said complementary means to trip said cycling mechanism, as the carriage takes the 40 usual feeding step upon the setting up of the last figure of an amount in any zone, to thereby provide for cross-computing the amounts indexed in said zones, the second part of said two-part dog-device being idly by-passed relatively to said complementary means before the carriage reaches the last denomination in a zone, whereby said second part becomes effective, in lieu of said first part, to coact with said complementary means to trip said cycling mechanism 50 during a return movement of the carriage from a zone should said return movement be started prematurely in such wise as to prevent the carriage from taking said step upon which the first part of said two-part dog-device depended to 55 come into play.

4. In a combined typewriting and computing machine, the combination with numeral-type keys and a step-by-step feeding carriage co-operative with said keys to set up an amount in 65 computing devices preparatory to a cycling operation, power-driven mechanism for returning said carriage, and a starting key for said returning mechanism, of carriage-controlled cycling mechanism including tappet-means and a co-operative unitary dog-device having two pawls pivoted thereon, said tappet-means and dog device being relatively adjustable in the direction of carriage travel, for a computing zone and co-operating by means of the carriage movement to 70 75

- trip said cycling mechanism for said zone, one of said pawls being engageable with said tappet-means to trip said cycling mechanism as the carriage advances in the usual letter step movement 5 upon the setting up of the last figure of an amount, the other pawl being idly by-passed by said tappet-means before the carriage reaches the last denomination in the zone but co-operative with said tappet-means to trip said cycling mechanism during a return movement of the carriage from the zone should said return movement be prematurely started after the tappet has passed said second pawl but before said tappet has tripped said first pawl.
- 10 15. In a combined typewriting and computing machine, the combination with numeral-type keys, a step-by-step feeding carriage, power-driven mechanism for returning said carriage, a starting key for said returning mechanism, and set-up means in which an amount is set up under the control of said keys and carriage preparatory to a cycling operation, of cycling mechanism automatically operated by said carriage at each of successive zones of the carriage 20 travel to accumulate the amount for said zone in a set of register-wheels and clear said set-up means preparatory to setting up an amount for the next zone, said cycling mechanism including a plurality of carriage-tappets, one for each zone 25 and adjustable therefor on the carriage, and a lever carrying a first and second pawl thereon connected to trip said cycling mechanism and operable by any tappet, the first pawl being engaged by said tappet to trip the cycling mechanism as the carriage advances in the usual step after the setting up of the last figure of an amount in a zone corresponding to said tappet, the second pawl being idly by-passed by said

tappet before the latter engages the first pawl but co-operative with said second pawl to trip said cycling mechanism during a return movement of the carriage from the zone should said return movement be prematurely started after the tappet has passed said second pawl but before said tappet has tripped said first pawl.

5 6. In a combined typewriting and computing machine having a key-operated step-by-step feeding carriage, tappets thereon and set-up 10 means in which an amount is set up under control of the keys and carriage preparatory to a cycling operation, power-driven mechanism for returning said carriage, and a starting key for said returning mechanism, cycling mechanism including a tripping train therefor, said tripping train having therein a single lever carrying a first and second pawl thereon engageable by said carriage-tappets, one tappet for each zone and adjustable therefor on the carriage, the first pawl being engaged by a tappet as the carriage advances in the usual step, after the setting up of the last figure of an amount in a zone corresponding to said tappet, to thereby trip the cycling mechanism for clearing the set-up 15 means preparatory to setting up an amount for the next zone, said second pawl of said tripping-train being idly by-passed by said tappets before the latter engages said first pawl, said tappet and said second pawl in lieu of said first pawl becoming effective to start said cycling mechanism during a return movement of the carriage from the zone should said return movement be prematurely started after the second pawl has been passed by said tappet but before said first pawl 20 25 30 35 has been tripped by said tappet.

WALTER T. SAGNER.
